UNITED STATES PATENT OFFICE.

ANDREW THOMA, OF CAMBRIDGE, MASSACHUSETTS, ASSIGNOR TO THOMA CORPORATION, OF PORTLAND, MAINE, A CORPORATION OF MAINE.

MACHINE FOR APPLYING AND USING RESINOUS CEMENT IN THE MANUFACTURE OF INNERSOLES.

No. 926,712.

Specification of Letters Patent.

Patented June 29, 1909.

Application filed February 1, 1909. Serial No. 475,359.

To all whom it may concern:

Be it known that I, ANDREW THOMA, a citizen of the United States, and resident of Cambridge, in the county of Middlesex and 5 State of Massachusetts, have invented an Improvement in Machines for Applying and Using Resinous Cement in the Manufacture of Innersoles, of which the following description, in connection with the accompanying 10 drawings, is a specification, like numerals on the drawings representing like parts.

My invention is an improvement on the invention of my application Serial No. 465,907, filed December 4, 1908, and has 15 for its principal object the provision of means for more readily and neatly handling the canvas or duck in its wet-coated state.

In carrying out my invention I pass the duck through a body of cement, scraping 20 the cement into heaped up linear deposits of the wet sticky cement, and then pass the fabric, with its sticky side up, over a continuously driven feed wheel in contact with a shield inclined so that a slight pull on the 25 fabric will bring it into driven contact with said feed wheel, a cutting device being located approximately on a level with the top of the feed wheel so that as the sticky duck is raised by the engagement therewith of an 30 innersole, it is naturally brought into position to be cut, the length of the feed wheel and position of the shield permitting the cutting thereof without disturbing the plane position of the sticky fabric, and the construction of the cutter and its relation to the 35 shield permitting the sticky fabric to drop onto the shield, as the end is severed therefrom, without smearing the machine with cement, sticking the hands of the operator, 40 sticking the cutter or interfering with the continuous and neat operation of the entire machine in any way.

The advantages of my invention will be further explained in the course of the following description, taken in connection with the accompanying drawings, in which I have illustrated a preferred embodiment of the entire machine.

In the drawings, Figure 1 shows the machine partly in longitudinal section and 50 mainly in side elevation; Fig. 2 is an end view thereof partly broken away, viewing the cutter from the left hand side; Fig. 3 is a

top plan view thereof; Fig. 4 shows in elevation a detail of the cement-applying portion 55 of the apparatus; and Fig. 5 is a fragmentary view in elevation of a modified construction.

In the embodiment of my invention as shown in the apparatus of the drawings, cement is delivered from a steam-jacketed supply tank 1 having an outlet cock 2 opening at the desired cement level of a steam-jacketed delivery basin or tank 3. A pilot 4 directs the fabric 5 into the cement, being shown as hinged at 6, (Fig. 4) to turn out of 60 the basin for readily receiving said fabric at the beginning. The roll of fabric is pivoted on a bracket 7 and thence passes up over an inlet plate 8 mounted by parallel links 9 upon the top 10 of the tank so that when 65 said inlet plate 8 is pulled by the engagement of a finger with the hook 11 at the end thereof, the plate 8 will move a considerable distance to the left away from the pilot 4 for the convenience of properly placing the web 70 of fabric.

A notched scraper or delivery plate 12 is held adjustably by a thumb screw 13 in position to engage the surface of the fabric as the latter passes upwardly from the pilot 4. 80 Preferably a guide 14 depends between the two plates 8, 12, against which the fabric is held by said two plates for the best results. When thus positioned the fabric will hug the walls of the pilot or fabric-guiding and directing device 4 so that only the outer surface thereof is coated with cement, the opposite surface being maintained clean and entirely free of cement. Besides hinging this guiding device or pilot, the entire table or top 10 is 85 preferably hinged at 15, Fig. 4, for swinging open when it is desired to entirely open the tank for inspection, cleaning, etc. From the cement-applying delivery tank the fabric 5 is led up over a direction roll or wheel 16 and thence onto a shield-plate or table 17, 90 and over a feed wheel 18, a limited portion of which is exposed above the shield for driving purposes. This feed wheel is preferably made of wood or absorbent material, and is 100 soaked or coated with oil or other cement-repelling matter so that it will not inadvertently get a grip on the canvas when not desired, and also so that it will not create any undue heat or friction as it rotates under the 105 stationary canvas lying thereon, and so that

it will not pick up ravelings from the edges of the strip or cement, or anything else which is not wanted. The shield-plate 17 extends at each end of the feed wheel or roll 18 as indicated at 19, 20, Fig. 3 for a purpose presently explained, and thence extends obliquely downward as shown at 21, Fig. 1, constituting a receiving table. Above the lower end of this inclined table I mount a cutting device of any suitable kind, being herein shown as a high speed rotary cutter 22 mounted to operate with relation to a cutting table 23 approximately on a level with the feed wheel 18. The table overhangs as clearly shown in Fig. 2, leaving the entire space beneath it unoccupied, to permit the operator to pull the canvas downward and forward in an inclined path, thereby enabling the feed wheel to do the feeding of the fabric instead of requiring the operator to exert a strong pull for said purpose.

In the machine of my before mentioned application, considerable strength was required for pulling the fabric, due to the resistance of the pilot and the scraper and the heavy nature of the cement. However, by having a feed wheel so positioned that the fabric can be held downwardly thereover in the general direction of the inclined table 21, the fabric is fed readily forward whenever the operator slightly pulls the fabric or renders it sufficiently taut to be engaged strongly by the feed wheel, and yet I am enabled to use the stationary pilot stripping device or scraper and other frictional devices shown in the cement-applying portion of the apparatus, which I have found it very advantageous to use. The cutter is covered by a guard 24. The guard 24 at its left hand side is placed at a distance from the cutter such that when the toe end of an innersole 25 is rested against the same, the fabric, as shown in Fig. 1, will be cut at the right distance from the rib 26 of the innersole so as to provide just the amount of fabric necessary for molding properly over the innersole.

In the drawings a Gem innersole is shown, and it will be understood that the shield will vary according to the kind of innersole with which it is desired to be used, as for example a Johnson innersole requires less duck than a Gem innersole, and therefore the left hand wall of the guard will be closer to the cutter for a Johnson innersole than for a Gem innersole. The opposite edge 27 of the guard is preferably shorter than the guiding side of said guard, so as to enable the operator, if he desires, to take hold of the forward edge of the canvas at that side of the machine and aid in pulling it forward. I find that some operators prefer to do this, although it is not the best practice.

Beneath the table 23 I suspend an oil well 28 in which the cutter runs, for maintaining the cutter smeared with oil, which I have

found greatly facilitates its cutting through the duck with its comparatively heavy coating of wet cement.

Any suitable driving mechanism may be employed, power being herein shown as communicated by a grooved belt pulley 29 to a shaft 30 at one end of which is a beveled pinion 31 in engagement with a gear 32 for driving the feed wheel 18, and at the opposite end of said shaft 30 is a pulley 33 belted at 34 to a small driving pulley 35 on the cutter spindle 36, the purpose being to drive the cutter at high speed and the feed wheel at low speed.

In use, the fabric having been led through the machine as shown in Fig. 1, the operator lays the side of an innersole containing the stitch-receiving lip or rib flat against the end of the cement coated surface of the fabric so that the end of the fabric comes at the desired point in the shank of the innersole as indicated in Fig. 3, and then pulls forward very slightly on the innersole and fabric with the result that the feed wheel immediately feeds the fabric forward without appreciable effort of the operator. When fed forward sufficiently the operator instantly raises the web of fabric to a level with the cutting table and directs the front longitudinal edge of the fabric against the cutter, the toe end of the innersole being guided by the guard 24. The rotary cutter severs the canvas leaving the right amount stuck on the innersole, and the rest of the fabric drops of itself back to its original position on the inclined shield table. The shield portions 19, 20 receive the edges of the fabric and coöperate with the inclined portion of the shield to prevent the fabric being improperly engaged by the feeding wheel. A further function of the lateral shield portion 19 is to receive the fabric as it is slewed laterally widthwise in the cutting operation. Also said portions 19, 20 hold up the edges of the fabric so that they cannot possibly curl against the feed wheel. It will be understood that the cement is so sticky and tenacious that the slightest amount on the feed wheel, or in fact on any other moving part of the mechanism, would be disastrous. As soon as the fabric is cut it automatically restores itself by dropping to operative position ready to receive another innersole, and by having the receiving table inclined, the result is that when the operator places the innersole on the coated fabric his first movement thereafter is naturally such as to bring the feed wheel into feeding operation. The operator usually takes up the innersole by the heel end with his left hand, and then places the toe end downward on the fabric at the right, whereupon he presses against the innersole just back of the toe with his right hand and this pressing action of the right hand produces the desired tension on the fabric over the feed wheel. The natural movement is not only a downward pressure,

but as the shield or receiving table is inclined, it is at the same time a forward movement, so that when the toe end of the innersole has reached alinement with the cutting apparatus, the operator at once raises the innersole and fabric to a level position at the cutting table and this again automatically, *i. e.* without thought or skill on the part of the operator, produces enough slack in the 16 canvas strip, or in other words relieves the tension or frictional engagement on the drive wheel sufficiently, to prevent any possibility of undesired feeding of the fabric. Also the relative positions of the parts is such that in 15 that position the fabric cannot be sufficiently engaged by the feed wheel to be driven thereby when slack. The guard at the cutter, in addition to serving the usual function of a guard, serves the more important function of 20 forming a definite measure between the cut-off portion of the canvas and the toe of the innersole. The side of the guard opposite the guiding or measuring portion thereof is preferably higher so as to permit the operator, when necessary, to place his finger beneath the fabric for aiding in guiding or controlling it.

By having the cutter constantly smeared with oil (or equivalent fatty or soapy matter) 30 a clean cut is always insured notwithstanding the fact that the cement is soft and exceedingly sticky at that time. The main purpose is to keep the cutter in a constantly cement-repellent condition, whether by oil or other 35 agency. Also it will be understood that while I have herein spoken of a reinforcing fabric rendered sticky by the application of a coating of hot cement, I do not intend to restrict my invention to this particular means 40 of rendering the fabric sticky, inasmuch as my invention is applicable to any of the cement-coated reinforcing fabrics and the methods of rendering them sticky, disclosed in my previous patents and otherwise known 45 in this art. I use the word "wet" to include all melted or sticky, smeary, or freely tacky conditions as distinguished from dry or non-sticky, etc. conditions, irrespective of whether the cement is freshly applied or not. 50 The free end of the cement-covered duck or canvas takes care of itself, leaving both hands of the operator free to manipulate the innersole. This enables the operator to use both hands in gripping the innersole so that he can 55 bring pressure upon the canvas next to the channeled part adjacent the heel. The subsequent "gemming" operation on the innersole begins at this point, and the firm contact between the canvas and innersole thus produced at this point by the operator greatly 60 facilitates the following "gemming" operation. Also by thus rendering the operator's hands free, he works more rapidly and with more comfort, and does his work more uni-

formly, and with great neatness, accuracy 65 and despatch. I prefer to have a guide wheel in addition to the feed wheel, as thereby I find that better results follow, but fairly satisfactory results may be secured by combining the functions of both parts in one as shown 70 in Fig. 5, in which case the shield terminates at 37. Also I wish it understood that I consider my invention broadly new in its provision of power operated means enabling the operator to feed and cut off a section of limp 75 canvas covered with fresh or wet cement, without smearing the innersole or cutting appliances.

This mechanism is the first attempt, so far as I am aware, in connection with a sticky 80 coated innersole reinforcing strip, either to feed the same otherwise than by hand from the mechanism rendering the strip sticky, or to cut off the innersole-engaged end of said sticky strip otherwise than by hand, so that 85 I intend my claims to be broad as to these features. And in general it will be understood that my invention is capable of wide variations in its mechanical embodiments without departing from the spirit and scope 90 of the invention as set forth in the following claims.

Having described my invention, what I claim as new and desire to secure by Letters Patent is:

1. In a machine of the kind described, means for delivering a cementitiously coated strip of innersole reinforcing fabric in a sticky condition on one side only, combined with feeding mechanism for feeding said sticky 100 strip forward, in position to receive an innersole, without being rendered ineffective by said sticky coating.

2. In a machine of the kind described, means for delivering a cementitiously coated strip of innersole reinforcing fabric in a sticky condition on one side only, combined with power-operated feeding mechanism for feeding said sticky strip forward, in position to receive an innersole, without being rendered 110 ineffective by said sticky coating.

3. In a machine of the kind described, means for delivering a cementitiously coated strip of innersole reinforcing fabric in a sticky condition on one side only, combined with 115 cutting mechanism for severing individual innersole reinforcing portions in succession from the end of said sticky strip as it is delivered in its said sticky condition, without being rendered ineffective by said sticky 120 coating.

4. In a machine of the kind described, means for delivering a cementitiously coated strip of innersole reinforcing fabric in a sticky condition on one side only, combined with 125 power-operated cutting mechanism for severing individual innersole reinforcing portions in succession from the end of said sticky strip

as it is delivered in its said sticky condition, without being rendered ineffective by said sticky coating.

5. In a machine of the kind described, 5 means for delivering a cementitiously coated strip of innersole reinforcing fabric in a sticky condition on one side only, combined with power-driven feeding mechanism for feeding said sticky strip forward in position to receive an innersole, and power-driven cutting mechanism for severing individual innersole reinforcing portions in succession from the end of said sticky strip as the latter is fed forward by said feeding mechanism.
- 10 15 6. In a machine of the kind described, mechanism for coating one side of a canvas strip with sticky cement including means for restricting said cement entirely to one side of the canvas and means for definitely regulating the sticky side thereof, combined with a severing mechanism for cutting off the innersole 35

mechanism from the strip.

7. In a machine of the kind described, mechanism for feeding a strip of reinforcing

canvas whose exposed side has a cementitious coating in a wet, smeary condition,

means for supporting said feed strip in position to receive an innersole against the sticky side thereof, combined with a severing

mechanism for cutting off the innersole in a

severed position from the strip, including the means for severing the severing mechanism to operate on the canvas while still wet and smeary without interference from its stickiness.

8. In a machine of the kind described,

mechanism for feeding a strip of reinforcing

canvas whose exposed side has a cementitious coating in a wet, smeary condition,

means for supporting said feed strip in position to receive an innersole against the sticky

side thereof, combined with a power-driven

severing mechanism for cutting off the in-

nersole, combined with a power-driven

severing mechanism for severing the severing

mechanism to operate on the canvas while still wet and smeary without interference from its stickiness.

9. In a machine of the kind described,

mechanism for feeding a strip of reinforcing

canvas whose exposed side has a cementitious

coating in a wet, smeary condition,

means for supporting said feed strip in position to receive an innersole against the sticky

side thereof, combined with a power-driven

severing mechanism for cutting off the in-

nersole, combined with a power-driven

severing mechanism for severing the severing

mechanism to operate on the canvas while still wet and smeary without interference from its stickiness, and means for permitting the canvas to automatically move forward to a receiving position.

10. In a machine of the kind described,

power-driven feeding means for delivering a

strip of canvas whose exposed side has a cementitious coating in a wet, smeary condition,

in position to receive an innersole against the sticky

side thereof, and severing means for

severing the innersole from the strip, the ad-

hesive mechanism including means for permitting

the canvas to automatically move forward to a

receiving position while being severed.

11. In a machine of the kind described,

power-driven feeding means for delivering a

strip of canvas whose exposed side has a

cementitious coating in a wet, smeary condition,

restricting said cement entirely to one side of

the canvas and means for definitely regulat-

ing the amount of cement left on the coated

side, combined with means for supporting

the free end of the cement covered canvas in

position permitting the innersole to be

pressed onto the coated side thereof, and

power-operated mechanism for cutting the

innersole-engaged portion of said canvas

strip from the rest of the strip while the ce- 70
ment is still wet and smeary, including means
for gaging the point of severance of the can-
vas surface to the toe end of the innersole.
75

10. In a machine of the kind described,
mechanism for feeding a strip of reinforcing 80
canvas whose exposed side has a cementitious
coating in a wet, smeary condition, and
means for supporting said fed strip in posi-
tion to receive an innersole against the

sticky side thereof, combined with a severing
mechanism for cutting off the innersole
engaged portion from the strip.

11. In a machine of the kind described,
mechanism for feeding a strip of reinforcing
canvas whose exposed side has a cementitious
coating in a wet, smeary condition,
means for supporting said feed strip in position
to receive an innersole against the sticky
side thereof, combined with a severing
mechanism for cutting off the innersole in a

severed position from the strip, including
the means for severing the severing mechanism
to operate on the canvas while still wet
and smeary without interference from its
stickiness.

12. In a machine of the kind described,
mechanism for feeding a strip of reinforcing
canvas whose exposed side has a cementitious
coating in a wet, smeary condition,
means for supporting said feed strip in position
to receive an innersole against the sticky
side thereof, combined with a power-driven
severing mechanism for cutting off the in-

nersole, combined with a power-driven
severing mechanism for severing the severing
mechanism to operate on the canvas while still wet
and smeary without interference from its
stickiness, and means for permitting the

canvas to automatically move forward to a
receiving position while being severed.

13. In a machine of the kind described,
power-driven feeding means for delivering a

strip of canvas whose exposed side has a

cementitious coating in a wet, smeary condition,

restricting said cement entirely to one side of

the canvas and means for definitely regulat-

ing the amount of cement left on the coated

dition, in position to receive an innersole against the sticky side thereof, and severing means to sever the innersole-engaged portion of the canvas from the end of the strip, 5 said feeding means being normally ineffective for feeding but rendered effective by a slight forward strain on the strip, the aforesaid mechanism including means permitting the canvas to halt automatically its feeding 10 movement while being severed.

15. In a machine of the kind described, feeding means for delivering a strip of canvas whose exposed side has a wet, smeary cementitious coating in position to receive an inner- 15 sole against the sticky side thereof, and severing means to sever the innersole-engaged portion from the end of said strip, said severing means being so located that when the strip has been fed in line therewith, the 20 presentation of the strip to the severing means produces a slack condition in the portion of the strip between the severing means and feeding means.

16. In a machine of the kind described, a 25 feeding wheel for feeding a strip of canvas whose exposed side has a cementitious coating in a wet, smeary condition, a receiving table inclined downwardly from said wheel to support the end of the canvas in position 30 to receive the innersole upon the sticky surface of the canvas, and a severing mechanism above the lower end of said table in position to sever the innersole-engaged portion from the end of the strip when raised free from 35 said table.

17. In a machine of the kind described, a feed wheel for feeding a strip of canvas whose exposed side has a cementitious coating in a wet, smeary condition, a severing device in 40 line with said feed wheel, and a shield at one end of said feed wheel for supporting the edge of the canvas when the strip is slewed widthwise to be severed.

18. In a machine of the kind described, a 45 feed wheel for feeding a strip of canvas whose exposed side has a cementitious coating in a wet, smeary condition, a severing device in line with said feed wheel, a table for receiving the strip when fed forward by said feed wheel 50 and positioning the same to receive an innersole on the sticky side of the canvas, said table being on a lower plane than said severing device, the machine having an open space between said severing device and feed wheel 55 to permit the end of the strip to fall on said table when the innersole-engaged portion thereof has been cut from said end.

19. In a machine of the kind described, feeding means for feeding a strip of canvas 60 whose outer surface has a sticky coating, means for keeping the feeding means uncontaminated by the work being fed, a cutting device for cutting off an end portion from said strip after an innersole has been stuck to 65 said end portion by said coating, and guiding

means for regulating the position of the cut with relation to the toe edge of the innersole.

20. In a machine of the kind described, feeding means for feeding a strip of canvas whose outer surface has a sticky coating, 70 means for keeping the feeding means uncontaminated by the work being fed, a power-driven rotary cutter for cutting off an end portion from said strip after an innersole has been stuck to said end portion by said coating, 75 and guiding means at the side of said cutter away from said feeding means for regulating the position of the cut with relation to the toe edge of the innersole.

21. In a machine of the kind described, 80 means for feeding a strip of canvas whose exposed side has a sticky coating, an inclined table extending downwardly from said means for supporting the forward end of the strip, a transversely arranged rotary cutter 85 above the lower end of said table in position to cut off the forward end of said strip when raised thereto from said table, and a cutting table for said cutter terminating at its end toward the feeding means approximately at 90 the cutter, whereby when an end portion of the strip is cut therefrom the remaining portion which extends back to the feeding means will fall back onto said inclined table.

22. In a machine of the kind described, 95 means for delivering a strip of innersole reinforcing canvas with one side coated with a wet smeary cementitious coating for receiving an innersole, combined with a transverse cutter for cutting off an end portion of said 100 reinforcing strip, and means for maintaining the cutting portion of said cutter in a cement-repellent condition whereby it is capable of continued service without being rendered ineffective by said smeary coating. 105

23. In a machine of the kind described, means for delivering a strip of innersole reinforcing canvas with one side coated with a wet smeary cementitious coating for receiving an innersole, combined with a transverse 110 cutter for cutting off an end portion of said reinforcing strip, and means for continually covering the cutting portion of said cutter with a cement-repellent medium for enabling the cutter to keep clean while cutting through 115 the sticky strip.

24. In a machine of the kind described, means for delivering a strip of innersole reinforcing canvas with one side coated with a wet smeary cementitious coating for receiving an innersole, combined with a transverse 120 rotary cutter for cutting off an end portion of said reinforcing strip, and an oil well containing cement-repellent liquid in which said rotary cutter turns for enabling the cutter to 125 keep clean while cutting through the sticky strip.

25. In a machine of the kind described, means for delivering a strip of innersole reinforcing fabric with one side coated with a hot 130

sticky cementitious coating, power-operated feeding means for feeding said strip intermittently forward, including means for keeping the feeding means uncontaminated because of the heated cementitious condition of the work, and power-operated cutting means for transversely severing the strip while still in said sticky condition, including means for keeping the cutting means uncontaminated by said sticky coating.

26. In a machine of the kind described, means for delivering a strip of innersole reinforcing fabric with one side provided with a wet sticky coating, a continuously driven feed wheel over which said strip passes, an inclined shield extending downwardly from said feed wheel for supporting said strip in position to be brought into driven contact with the feed wheel by a slight pull on the forward end of the strip, a transverse cutting device located approximately on a level with the top of the feed wheel in position to receive and cut off an end portion from said strip when raised thereto, said feed wheel and cutting device being located relatively to each other and to the normal position of the strip to prevent the feeding of the strip by the feed wheel when the strip is raised for cutting, and the length and position of the feed wheel permitting the cutting of the

fabric widthwise without disturbing the plane position of the sticky strip.

27. In a machine of the kind described, means for delivering a strip of innersole reinforcing canvas with one side provided with a cementitious coating in a sticky condition, a continuously rotating feed wheel over which said strip passes from said delivery means, a shield for restricting the area of said feed wheel exposed to the canvas strip, a receiving table for supporting the forward end of said strip in a downwardly inclined position, transverse cutting mechanism mounted above the lower end of said receiving table, said cutting mechanism including an overhanging cutting table in line with said feed wheel, leaving the space beneath said cutting table above said receiving table clear for the forward movement of the operator's hand in guiding and pulling the canvas in a downward and forward inclined path whereby the canvas is maintained in feeding engagement with said feed wheel.

In testimony whereof, I have signed my name to this specification, in the presence of two subscribing witnesses.

ANDREW THOMA.
